UNITED STATES PATENT OFFICE.

CHARLES A. KUSTER, OF NEW YORK, N. Y., ASSIGNOR TO BILTMORE LIGHTING FIXTURE CO., A PARTNERSHIP, OF BROOKLYN, NEW YORK.

DESIGN FOR A SUPPORTING RING FOR LIGHTING FIXTURES.

Application filed November 20, 1924. Serial No. 11,421. Term of patent 7 years.

To all whom it may concern:

Be it known that I, CHARLES A. KUSTER, a citizen of the United States and a resident of the borough of Queens, Queens county, city and State of New York, have invented a new, original, and ornamental Design for a Supporting Ring for a Lighting Fixture, of which the following is a specification, reference being had to the accompanying drawing, forming a part thereof.

Fig. 1 is a side view partly in section; and

Fig. 2 is a bottom plan view of a supporting ring for a lighting fixture showing my new design.

I claim:

The ornamental design for a supporting ring for a lighting fixture, as shown.

CHARLES A. KUSTER.
